UNITED STATES PATENT OFFICE.

JUDSON A. LAMON, OF MONTCLAIR, NEW JERSEY, ASSIGNOR TO MCCORD & COMPANY, OF CHICAGO, ILLINOIS, A CORPORATION OF NEW JERSEY.

COMPOSITE JOURNAL-BOX FOR CAR-TRUCKS.

1,245,471.

Specification of Letters Patent.

Patented Nov. 6, 1917.

Application filed May 3, 1916. Serial No. 95,041.

To all whom it may concern:

Be it known that I, JUDSON A. LAMON, citizen of the United States, residing at Montclair, in the county of Essex and State 5 of New Jersey, have invented certain new and useful Improvements in Composite Journal-Boxes for Car-Trucks; and I do hereby declare the following to be a full, clear, and exact description of the invention, such as 10 will enable others skilled in the art to which it appertains to make and use the same.

My invention relates to journal boxes for car trucks, and has for its object to provide an improvement in that class, or kind which 15 might well be called composite boxes to distinguish the same from the older, or integral casting kind or class of boxes. In the integral casting kind, the top and the cellar are cast integral with each other, and if left 20 unannealed are known as gray iron boxes and, if subsequently annealed, are known as malleable iron boxes.

The composite boxes are of two species. The older species—such as the box of the 25 Schoen Patent, 482,200, of September 6, 1892, and of the Woods Patents, 904,665, of November 24, 1908, and 969,933, of September 13, 1910,—are usually composed of cast metal tops and sheet metal cellars, first sepa- 30 rately and independently made, and then subsequently assembled and riveted together; and hence, by the removal of the rivets, the top and the cellar may be again sepa- 35 rated and then be in their original forms. These may, therefore, be well called, separable composite boxes.

The newer species of composite box is the invention of Ivar A. Randel; and, in its original form, was first disclosed and claimed 40 in his Patent, 1,077,159, of October 28, 1913; and in its improved form, it is disclosed in his Patent, 1,090,085 of March 10, 1914; and the process, by which he produces his box, in this improved form, is disclosed and 45 claimed in his Patent 1,089,585, of March 10, 1914.

If reference be made to these Randel patents, it will be seen that the cellar of sheet steel is first independently formed by the use 50 of suitable dies, and then that the said cellar is placed in a suitable mold and the top is cast fast to the cellar, and is itself formed in the casting operation. Because of this new process of manufacture, the top and the

cellar are integrally connected, and never 55 can again be separated, and the integrity of the original cellar be preserved; and, of course, there was no original separately made top to be preserved. Moreover, no separation can be made between the cellar and the 60 top of the Randel box which will maintain a top of cast metal alone, or any top capable of re-use with any cellar. Of course, the box may be sawed through, on horizontal planes, and this sawing could separate a sheet metal 65 portion of the cellar from an upper portion of the box which would be composed chiefly of the cast metal of the top, but which would, of necessity, still have integral therewith some portions of the sheet metal of the cellar. 70

From the practical or commercial stand-point, therefore, the connection between the top and the cellar of the Randel box is an integral one; and the character of the connection is mechanically just as complete, for 75 all practical or commercial purposes, as the connection between the metal of the top and the metal of the bodies or cellars of any of the old malleable iron integral casting boxes. Hence, the Randel box may well be 80 characterized as an integral composite box.

In all journal boxes for car trucks, the strains incidental to the service, come almost solely on the top, including the stop lugs, for the brass and the key, which stop lugs 85 are usually formed integral with and constitute a part of the top; and moreover, these strains are chiefly taken at the central zone of the top portion of the box. The cellar is practically simply a container for 90 oil and waste, and must also be adapted to exclude sand, dust, and dirt, and retain the oil without leakage. For the reasons above stated, the top of the box must have great strength to resist the strains of the service, 95 and is always rigid and massive, and relatively heavy as compared with the cellar which may be, and usually is, comparatively light. The composite box is much lighter than the gray iron or malleable iron integral 100 casting boxes, because sheet metal, usually plate steel, brought into the desired shape by the use of proper dies, is employed for the cellar; and the effort has been, and still is, to further lighten or reduce the weight 105 of these composite boxes by distributing the metal of the top to better advantage.

This is the precise purpose of my inven-

tion, which consists of the novel features hereinafter described, and defined in the claims.

Although my invention is capable of use 5 on both species of composite boxes, above identified and distinguished, it was specially designed to afford an improved composite box of the Randel or integral composite type; and hence, is so illustrated in the 10 drawings.

In said drawings, like notations refer to like parts, throughout the several views; and, therein,

Figure 1 is a view in side elevation showing my improved box with some parts removed;

Fig. 2 is a view chiefly in plan, looking down on the top of the box, but with a portion of the top broken away, and a portion 20 of one side, and the rear end of the box, shown in horizontal section on the line x^2-x^2 of Fig. 1;

Fig. 3 is a view of the box chiefly in front elevation, but with a portion thereof shown 25 in vertical section, on the line x^3-x^3 of Figs. 1 and 2; and

Fig. 4 is a fractional view, partly in front end elevation, but chiefly in vertical section on the line x^4-x^4 of Figs. 1 and 2.

The numeral 1 represents the pressed steel 30 sheet metal cellar brought to the desired form by the use of suitable dies, and with the exceptions hereinafter noted is, or may be, of substantially the same form as that 35 shown in the Randel patents above identified. The most important exception or difference necessary here to note, is that my improved cellar 1 is provided at its central zone with two outwardly extending corrugations a , and one inwardly extending corrugation b . The inwardly extending corrugation b extends for practically the full 40 height of the side wall of the box, and the pair of corrugations a are spaced apart from 45 each other and coöperate with the inward corrugation b to afford a seat for the journal bolts (not shown). The pair of corrugations a are of flaring form, increasing upward, with their lower or smaller ends 50 merged into the main plane of the side wall of the cellar, and their upper or larger ends open and terminating in the same horizontal plane as the other portions of the side wall of the cellar, as clearly shown in the drawing.

The cellar so formed is placed in a suitable mold, and the top 2 is formed and cast fast thereto by the process disclosed in the 60 said Randel Patent, 1,089,585, steel being preferably used as the metal. The mold (not shown) is of such shape that portions of the molten metal will embrace the upper edges of the cellar, at all parts thereof, except at the central zone, and fuse therewith, 65 and shrink fast thereto, and the other por-

tions of the molten metal will run through holes provided in the upper edges of the cellar, and cross-bond together the portions of the top which so embrace the edges of the cellar, all as disclosed in said Randel 70 patents; and, the mold is further of such shape, that when the casting is completed, the top will have depending stop lugs c , on the inside of the cellar, and a flat arch bar seat d on its top with projecting bolt lug flanges d' overreaching the side walls of the said 75 cellar, and reinforcing ribs e formed integral with the stop lugs c and the said projecting bolt lugs d' of the arch bar seat. Otherwise stated, in the casting operation, 80 the molten metal will run into and fill the flaring corrugations a of the cellar, and will also surround the upper portion of the straight corrugations b and will be fused 85 fast to the walls of all three of these corrugations, and thereby the projecting portion of the arch bar seat of the top, to-wit, the bolt lug d' , and the stop lugs c will be connected together and reinforced by the 90 said ribs e —all portions of this mass of metal being integral. In this way, a top of 95 great strength is secured, at the places where most needed, to wit, at the central zone, under the projecting portions of the arch bar seat, and directly opposite the stop lugs c . The cellar is of such shape as to afford a 100 flat tie bar seat f , on its bottom, in the same vertical plane as the arch bar seat of its top, and, when the journal bolts (not shown) are applied to connect the box to a truck of the arch bar type, they pass through the 105 holes in the projecting portions or bolt lugs d' of the arch bar seat and are themselves seated in the vertical corrugations b and between the flaring corrugations a of the 110 cellar.

The mold is also of such shape that none of the molten metal embraces the upper edges 115 of the cellar at the central zone of the box, to-wit, none of those portions having the corrugations a and b ; and hence, when the box is completed, these corrugated portions of the upper edges of the cellar, simply abut against the side projecting ends or bolt lug portions d' of the arch bar seat, as best 120 shown in Figs. 1, 3, and 4 of the drawing.

From the foregoing, it must be obvious, that in virtue of my improvement, I am 125 able to distribute the metal of the top in a way most advantageous, for getting strength where most needed; and at the same time, am able to get a sheet metal cellar which is integrally connected to the top, and therefore, free from any joints which could open to admit sand, dust, or dirt, or permit the escape of oil under the vibrations incidental to the service.

If my invention, herein disclosed and claimed, was to be applied to a separable composite box, the cellar and the top would, 130

of course, be first separately made, and then subsequently assembled and riveted or otherwise secured together, and the cellar would have the same corrugations *a* and *b* as here shown, and the top would be of the same general shape, and provided with the stop lugs *c*, bolt lugs *d'*, and the reinforcing ribs *e* formed integral with each other; and, when assembled, these parts of the top and the cellar would occupy the same relation to each other as in the box illustrated.

My improved box, when made by the Randel process, does not cost any more than the original Randel box. Of course, it must be understood that proportions and weights of the different parts, especially of the top, will vary for different sizes of boxes, as required for cars of different capacities.

It should also be understood that the mold may be of such shape that the molten metal would embrace the whole of the upper edges of the cellar and be cast fast thereto, as in the Randel boxes, so that the completed box would have continuous flanges embracing the upper edges of the cellar. The continuity of the outer flanges, however, is not essential. The central portions may be omitted so as to afford gaps in the outer flanges in that part of the box directly under the projecting ends or bolt

lug portions *d'* of the arch bar seat *d*, as illustrated in the drawings; and, the box has been so illustrated to show that this can be done, without materially weakening the box, or producing any open joints between the top and the cellar.

What I claim is:

A journal box comprising an independently formed metallic cellar and a top of cast metal cast fast to said cellar, the sides of said cellar having pairs of outstanding laterally spaced corrugations that extend from the extreme upper edges of said sides and taper downwardly and blend into the sides of said cellar, and said cast top having integral stop lugs cast against the inner surfaces of the sides of said cellar, and in turn, having tapered reinforcing ribs cast into and fitting said tapered corrugations, and the said top further having overhanging bolt lug flanges, the under surfaces of which align with the upper edges of said corrugations, leaving the same exposed at the exterior of the cellar.

In testimony whereof I affix my signature in presence of two witnesses.
